UNITED STATES PATENT OFFICE.

EDWARD F. SEERY, OF PROVIDENCE, RHODE ISLAND.

DESIGN FOR AN ORNAMENTAL CHAIN-LINK.

SPECIFICATION forming part of Design No. 12,654, dated January 3, 1882.

Application filed November 11, 1881. Term of patent 7 years.

To all whom it may concern:

Be it known that I, EDWARD F. SEERY, of the city and county of Providence, State of Rhode Island, have invented and produced a new and original Design for Ornamental Chain-Links, of which the following is a full, clear, and exact description, reference being had to the accompanying drawings, forming part of this specification.

10 The leading feature of my newly-invented design consists in ornamenting the sleeve of a chain-link of uniform diameter with rings of the same or a different color as the sleeve, or with knurled or otherwise ornamented rings.

15 Figure 1 is a view of an ornamented chain-link in which a round tubular sleeve is ornamented by securing three rings on the sleeve. The connecting-links are also shown as ornamented with such rings. Fig. 2 is a view of

20 an ornamental chain-link, in which a square tubular sleeve is ornamented by securing three square rings on the sleeve, the connecting-links

being also ornamented by placing square rings over the same.

In the drawings, A A are the tubular sleeves; 25 B B, the ornamental rings placed on the sleeves, and C C the rings placed on the connecting-links to ornament the same.

Ornamental chain-links have heretofore been made in part of round or square tubes, and 30 such tubes have been used for sleeves. They have been ornamented by cutting, engraving, and slotting.

Having thus described my newly-invented design, I claim as new and desire to secure by 35 Letters Patent—

The design for ornamental chain-links herein shown and described, the same consisting of a tubular sleeve ornamented by rings forming raised surfaces on the same, as described. 40

EDWARD F. SEERY.
